PISTON

Leon A. Hallstead, Grand Island, N. Y.

Application November 16, 1938, Serial No. 240,832

4 Claims. (Cl. 309—15)

This invention relates to a piston and more particularly to a piston adapted for use in internal combustion motors and the principal object of the invention is to provide such a piston in which compression is insured by an expansible skirt having an upper flange arranged in an annular groove in the piston head, the clearance between the groove and flange being that customarily provided for piston rings. The invention is capable of use with or without piston rings.

One of the principal objects of the invention is to provide such a piston in which the skirt is so anchored in the piston head that it can float and move freely therein so as to readily adapt itself to the piston walls and in which the skirt is of uniform symmetrical form throughout, containing no masses of metal which would result in uneven expansion.

Another object of the present invention is to provide such a piston in which the skirt can be conveniently removed, the head being made, for this purpose, of two separate pieces separating along the line of the plane of the groove so that by separating the sections the skirt can be conveniently withdrawn.

Another object of the present invention is to provide such a skirt having an inwardly projecting flange at its upper end which is split at one side and in which an L-shaped recess is also provided on the outside of the piston at the upper end of the split, this recess receiving an L-shaped cover which extends along the upper part of the split and thereby avoids the danger of leakage through the split.

Another object of the present invention is to so construct the piston that the skirt may be removed and inserted from the top of the cylinder by the simple expedient of removing the upper section of the piston head and withdrawing the skirt.

Another purpose of the present invention is to provide means for preventing the skirt from turning relative to the piston head, except to a limited extent, by providing a screw in the piston head which extends through a hole provided in the upper flange of the skirt.

In the accompanying drawing:

Fig. 1 is a side elevation of a piston embodying my invention.

Fig. 2 is a vertical transverse sectional view therethrough.

Fig. 3 is a top elevation thereof, showing the same partly broken away.

Fig. 4 is a vertical sectional view taken on line 4—4, Fig. 2.

Fig. 5 is a bottom view.

Fig. 6 is a vertical sectional view through the upper section of a modified form of piston head, in which a piston ring is provided.

The piston head, shown in Figs. 1—5, is composed of a lower disk-shaped portion 10 which is of less diameter than the inside diameter of the skirt 11 so that the skirt 11 can be conveniently removed by lifting it free from the disk-shaped part 10. This excess size of the piston skirt 11 also permits the piston skirt to yield inwardly or "breathe" in traversing the cylinder wall, as hereinafter described. The lower section 10 of the piston head has the usual depending arms 12 which at their lower ends carry the wrist pin 13. The arms 12 are preferably reinforced by ribs 14 in any usual and well known manner.

The disk-shaped section 10 is provided with a threaded stud 15 and to this stud is secured the upper disk-shaped section 16 of the piston, this upper disk-shaped portion 16 having a neck or boss 17 which provides an annular groove 18 between the two sections.

The skirt 11 is of cylindrical form and is formed at its upper end to provide an inwardly projecting annular flange 19 which is disposed within the groove 18. The clearance between the top and bottom of the flange 19 and the annular groove 18 is preferably about .015 of an inch so that while the flange is positively held in the groove an oil seal is provided in the same manner as with piston rings. It will be seen that the skirt floats in the groove 18 so that it is free to move and yield in adapting itself to the cylinder walls. It will also be seen that the skirt has no concentrated masses of metal, such as bosses for the wrist pin, etc. By eliminating such concentrated masses of metal, there is no tendency to unevenness in expansion with resultant warping of the skirt.

The skirt 11 is split along one side, as indicated at 20, this split permitting the skirt to adapt itself to the size of the cylinder both initially and as the cylinder and skirt wears. This split extends through the cylindrical side of the skirt and also through the upper flange 19, preferably extending through the upper flange 19 radially, as indicated by dotted lines in Fig. 3, and preferably extending obliquely down the side of the skirt, as indicated in Fig. 1, so as to avoid the danger of scoring the cylinder wall. It is apparent that the flange 23 of the skirt is firmly held in the groove 18 and at the same time the

skirt is entirely free to yield inwardly and outwardly, having in the nature of a "floating" connection to the piston head, this connection thereby securely holding the skirt and at the same time permitting it to yield and adapt itself to the cylinder walls.

In order to hold the skirt 11 against turning relative to the head a screw 21 is provided. This screw preferably has its head countersunk in a recess 22 in the upper piston head section 16 and its threaded stem extends through a hole provided in the upper flange 19 of the skirt and into a threaded hole provided in the lower section 10 of the piston head. It is apparent that this screw not only prevents the skirt from turning, but also locks the upper and lower sections 10 and 16 of the head against turning relatively to one another so as to prevent these sections from loosening.

In order to prevent leakage through the split 20 in the skirt the upper flange 19 is provided with a shallow broad radial groove 23 which extends from either side of the radial split 20 in the flange 19, as best illustrated in Fig. 3. This groove 23 merges into another groove 24 provided in the outside of the skirt 11, this groove 24 extending obliquely down the side of the skirt with the split 20 at its center. This groove 24 preferably stops short of the bottom of the piston. In the grooves 23 and 24 is arranged an L-shaped cover 25, the upper part of which fits into the groove 23 and the side part of which fits the groove 24. This cover is made so that when inserted it forms a continuation of the outer wall of the skirt and serves to prevent leakage through the upper part of the split 20. A slight clearance of approximately .015 of an inch is left between the edges of this cover and the grooves 23 and 24 so as to provide an oil seal.

In assembling the piston the skirt is placed over the disk 10, the L-shaped cover 25 is placed in the grooves 23 and 24 and the upper section 16 of the head is then screwed down. The screw 21 is then inserted and the skirt is held against turning relative to the piston head and at the same time the two sections of the piston head are locked together. With this construction it is apparent that after the piston has been placed in the cylinder the skirt can be replaced by removing the cylinder head, removing the screw 21, unscrewing the upper section 16 of the piston head and lifting the skirt 11 out of the cylinder and replacing it with another one. It is also apparent that by the provision of the flange 19 closely held within the groove 18 with only enough clearance to provide an oil seal that the skirt is positively held in the head but is free to float therein and expand or contract to adapt itself to the cylinder walls. It is also apparent that there is no danger of leakage past the skirt particularly with the provision of the cover 24 which provides a seal around the upper part of the split through the skirt.

In Fig. 6 is illustrated a modified form of the upper section 16a of the piston head, this being generally similar to the piston head section 16 shown in the form of the invention illustrated

in Figs. 1-5, except that it is additionally provided with a piston ring groove 30 in which a conventional piston ring 31 is placed. The other parts of the piston head section 16a are substantially identical with the piston head section 16 and therefore the same reference numerals have been employed and distinguished by the suffix "a". It will be appreciated that the provision of the piston ring 31 further guards against leakage past the piston, the piston additionally having the advantages obtained by the provision of the floating skirt which has no concentrated masses of metal.

I claim as my invention:

1. A piston, comprising a lower head section, an upper head section, screw means connecting said head sections, said head sections when tightly connected providing between them an annular, peripheral groove of substantial depth which is closed at its inner end, a skirt fitting around said head and having an inwardly projecting annular flange slidingly and closely fitted in said groove, and a pin extending through one head section and skirt and into the other head section and restricting relative movement of said head and skirt and also preventing said head sections from unscrewing.

2. A piston, comprising a head, a skirt surrounding said head and having at one end an inwardly projecting annular flange engaging said head, said skirt and flange being provided with a continuous L-shaped split extending from one edge of said flange to the opposite edge of said skirt, means for securing said skirt to said head, the outer side of said flange being recessed around said split and said external recess extending along the side of said skirt around said split and an L-shaped cover in said recess and sealing the upper end of said split.

3. A piston, comprising a head having an annular peripheral groove, a skirt fitting around said head and having at one end an inwardly projecting annular flange yieldingly and closely fitted in said groove, said end flange being provided with a continuous L-shaped split extending from one edge of said flange to the opposite edge of said skirt, the outer side of said flange being recessed around said split and this recess being extended along the outside of said skirt around said split, and an L-shaped cover in said recess and sealing the upper end of said split.

4. A piston, comprising a lower head section, an upper head section, screw means connecting said head sections, said head sections when tightly connected providing between them an annular, peripheral groove of substantial depth, a skirt fitting around said head and having an inwardly projecting annular flange at one end closely fitted in said groove, said skirt and flange being provided with a continuous L-shaped split extending from one edge of said flange to the opposite edge of said skirt, the outer side of said flange being recessed around said split and this recess being extended along the outside of said skirt and said split and an L-shaped cover in said recess and sealing the upper end of said skirt.

LEON A. HALLSTEAD.
